UNITED STATES PATENT OFFICE.

LOUIS A. HAWTHORNE, OF NEWARK, NEW JERSEY, ASSIGNOR TO STEEL UTILITIES,
INCORPORATED, A CORPORATION OF NEW YORK.

METAL-WORKING MACHINE.

1,241,252.

Specification of Letters Patent. Patented Sept. 25, 1917.

Application filed March 13, 1914. Serial No. 824,386.

To all whom it may concern:

Be it known that I, LOUIS A. HAWTHORNE, a citizen of the United States, residing at Newark, New Jersey, have made certain 5 Improvements in Metal-Working Machines, of which the following is a specification.

The invention relates to machines for perforating structural shapes and the like for fabrication and more especially to distance 10 determining devices for properly feeding and locating the work with reference to perforating mechanisms.

Objects of the invention will be set forth hereinafter in part, and in part will be obvious herefrom, said objects being effected 15 and realized by the instrumentalities and combinations set forth in the appended claims.

The invention consists in the novel parts, 20 constructions, arrangements, combinations and improvements herein shown and described.

The accompanying drawings referred to herein and forming a part hereof, illustrate 25 one embodiment of the invention, and with the description serve to explain the principles thereof.

Of the drawings:

Figure 1 is a plan, with parts in section 30 and with parts broken away, of a machine embodying the invention;

Fig. 2 is a plan, on an enlarged scale, of the distance determining device shown in the lower central part of Fig. 1;

Fig. 3 is an elevation looking at Fig. 2 from the foot;

Fig. 4 is a vertical transverse section on the line A—B of Fig. 2;

Fig. 5 is a fragmentary isometric perspective of a part of the mechanism showing the 40 sliding plates and their stop keys or pins;

Fig. 6 is a fragmentary plan corresponding substantially to Fig. 5 and showing additional parts at the upper end;

Fig. 7 is a transverse section on the line 45 C—D of Fig. 2;

Fig. 7^a is an enlarged fragmentary detail of the lower right hand part of Fig. 7;

Fig. 8 is a detail plan of the grooved cylinder for the fraction of inches; and

Fig. 9 is an elevation looking at Fig. 8 from the foot.

Referring to the accompanying drawings, illustrating by way of example one embodiment of the invention, the invention is

shown applied to a machine in which the structural shape, or like work, is continuously frictionally impelled forward, and is controlled in its travel and stopping by a distance determining device having connections which move with the work and are stopped in accordance with the settings of the distance determining device to properly position the work for perforation by the punching mechanism, although in many of its aspects the invention is applicable to other kinds of shape punching machines.

As embodied, the shape *x*, shown as an I-beam, in Fig. 1, rests upon a substantially horizontal series of forwarding rollers 1. 70 The rollers 1 are driven in a suitable manner and are shown with their shafts 2 mounted in bearings 3. Fixed on the shafts 2 are beveled gears 4, which gears mesh with corresponding bevel gears 5 mounted on and fixed to rotate with driving shafts 6, the shafts 6 being supported in suitable bearings 7. In the illustrated form of machine, a shaft 6 is shown driving the rollers 1 on one side of the punching mechanism, and another 75 shaft 6 driving the rollers 1 on the other side thereof. The shafts 6 are driven in a suitable manner, as by a gear train 8 from a motor 9. The motor 9 is suitably controlled as to speed, started and stopped, 80 either manually by the operator or automatically by different parts or operations of the mechanism, or it may be controlled by an automatic device such as a distance record strip. The motor 9 may be connected or arranged to start and stop the rolls 1 when the shape *x* is held at rest by connections from an automatic distance record device such as a perforated sheet. The frames or housings 85 for a plurality of punching mechanisms are indicated generally by reference numeral 10, and the location of one or more sets of punching devices are indicated generally by reference characters *y* and *z*.

As embodied, the shape *x* has coöperating 95 therewith a head 15 against which the forward end of the shape abuts, permissive travel of head 15 determining the positioning of the shape relatively to the punches. Connected with the shape 15 is a long member 100 extending backward along the shape, and being preferably in the form of a bar 16. Said bar 16 is suitably supported in roller guides (not shown) and extends back 105 for the entire length of the shape *x*. The 110

rack 16 is provided in the embodied form with a series of gear teeth 17 upon the upper face thereof. Meshing with the gear teeth 17 is a pinion 18 upon a shaft 19 journaled in a bearing 20, the shaft 19 thus traveling proportionally to the shape or other work.

Settable devices representing distance denominations and distance values coöperate 10 to control the rotation of the shaft 19, permitting the shaft to rotate, with a corresponding forward travel of the rack 16 and head 15, to permit the shape α to move forward the exact distance for which said settable means were set by the operator, or by 15 a suitable automatic controlling device such as a perforated sheet or strip. As embodied, the shaft 19 is journaled in bushings 21 (Fig. 2) carried in bearings 22 at either end 20 of a hollow cylindrical casing 23.

Said casing 23 is provided with an interior thread 24, extending substantially from one end to the other thereof. The casing 23 is longitudinally apertured, having 25 substantially a quadrant of open space through which the connections between the interior and exterior mechanisms of the distance determining device pass and along which they travel.

30 Within said casing 23, the shaft 19 has a square portion, or is otherwise shaped to carry parts or members rotatable therewith but slidable thereon, said squared or like part being indicated by reference numeral 35 25. Mounted on said squared portion 25 is a nut 26 which fits interiorly said squared part 25, whereby the nut 26 rotates with the shaft 19 and is adapted also to slide thereon. The nut 26 has an external thread 27 meshing 40 with the thread 24 upon the interior of the casing 23, the nut 26 traveling along shaft 19 and along and within casing 23 as the shaft 19 rotates. Fixed to or integral 45 with the nut 26, and extending toward the right (referred to Fig. 2) is a sleeve 28, 50 interiorly apertured to fit the squared portion 25 of the shaft, and being externally of cylindrical form. Upon the end (to the right in Fig. 2) of the sleeve 28 is a suitable stop device for the purpose of holding in proper relation the parts mounted upon the sleeve 28, said stop device being shown as a collar 29 threaded onto the end of the sleeve.

55 Upon the sleeve 28 is journaled a cylindrical member 30 internally cylindrically apertured to rotate upon said sleeve 28. The cylinder 30 has integral therewith or fixed thereto a sleeve 31 (extending to the right 60 in Fig. 2), which sleeve 31 embraces the sleeve 28. The sleeve 31 is provided with an external thread 32. The sleeve 31 is slightly spaced away from the collar 29 for a purpose hereinafter to be described. Encircling the thread 32 of the sleeve 31 is an

internally threaded nut 33, having its internal thread meshing with the external thread 32 of the sleeve 31. Connected to the nut 33 is a neck piece 34, which extends outwardly through the longitudinally apertured portion of the cylinder 23.

Connected to the neck 34 of the nut 33 are a series of movable members, having according to certain features of the invention, translational movement with respect 75 to each other, which members are controlled by settable devices, such as groups of keys, to move desired distances, thereby effecting and controlling the progression and stopping of the shape with respect to the tool 80 equipped means to properly position the shape to receive the perforations. As embodied, the neck 34 connects to a plate 40. (See Figs. 4 and 5.) The plate 40 is slidably supported upon a bed 41 by suitable 85 bearing surfaces 42 and 43. Mounted upon the plate 40 is a plate 44, carrying a group or series of keys 45, which in the embodied form may be regarded as the inch keys and as being twelve in number.

The keys 45 are vertically reciprocable in apertures in the plate 44 and likewise in the plates 48 and 40, and when set or pressed downwardly the lower part of the key or pin is adapted to pass through the plate 40 90 into a slot in a plate or part beneath. The keys 45 are provided with restoring springs 46 suitably coiled between the key heads and the plate 44. Locking means are provided to hold a set or depressed key in set 95 position and to release it upon the setting or depressing of a subsequent key.

As embodied, the stems of the keys 45 are provided just beneath the plate 44 with conoidal enlargements 47, the large ends of 105 said conoidal portions abutting against the plate 44 and acting as stops when the keys are in the retracted position, as shown in Figs. 4 and 7. Just below the lower or small end of the conoidal enlargements 47 is 110 mounted a sliding plate 48 carried upon pins 49, and yieldingly held in one direction by springs 50. The plate 48 has openings 51 therein of a size just sufficient to permit the passing therethrough of the large end 115 of the conoidal portions 47 of the keys of the group. The spring 50 urges the plate 48 to one side, whereby the pins or keys 45 are at one side of the apertures 51. When any key is depressed or set, the conoidal 120 portion 47 thereof slides the plate 48 against the spring 50 until the conoidal portion 47 has passed through its aperture 51, whereupon the plate 48 is snapped back by the spring 50, and the plate acts as a stop just 125 back of the large end of the conoidal part of the set pin. The set key is thus held or locked in set position by the plate 48 until a new key is set. Upon the setting of a new key, the conoidal portion of such new key, 130

in passing through its aperture 51 in the plate 48 moves the plate 48 against spring 50 in the same way as the preceding key, and causes the first key to be released when 5 its aperture 51 again comes into line or register with the conoidal portion on said key.

In Figs. 7 and 7^a a key 52 is provided which normally engages the next sliding plate beneath the one on which said key is mounted. Said key is yieldingly held by a spring 53 in the position wherein it projects into an aperture in the plate beneath. The head of said key projects through a slot in a plate 54 which has a camming surface 55, and the plate 54 is impelled to the right by spring 56. The apertures 57 in plate 54 are on the opposite side from the corresponding aperture 51 in plate 48. When a key 45 is depressed, the plate 54 is consequently slid 10 to the left in Fig. 7^a and the key 52 is cammed up out of engagement with the plate beneath, at the same time that the depressed key 45 enters its slot in the plate underneath. When all keys 45 are retracted, 15 the key 52 is in locking position as shown. This device may be used also on an automatically operated keyboard, such as one operated electrically from a controlling strip or sheet.

30 Beneath the plate 40 is a plate 65, having sliding or translational movement, and provided with a key carrying plate 66, carried upon an enlarged end portion 67 thereof. In the key carrying plate 66 are mounted 35 a series of keys 68, which in the embodied form may stand for the feet, or rather for the denomination of units of feet. Said keys 68 may be provided with locking and restoring devices, such as already have been 40 described, and may be indicated by similar reference numerals. The keys or pins 68 have reciprocation in suitable apertures in the key carrying plate 66 and in the plate 65, and the set keys are projected into slots 45 in a suitable plate beneath the plate 65, the slots being proportioned to the numerical value of the corresponding key.

Underneath the plate 65 is a slideable plate 69, likewise having sliding or translational 50 movement, and provided with an enlarged portion 70. Mounted reciprocably on said enlarged portion is a bank of keys 71, which keys are also reciprocably carried in a plate 72. Said keys may be similar in construction to those previously described and no further description at this point will be necessary. When one of the keys 71 is set or depressed, it passes into a slot in a plate beneath the plate 69. In the embodied form 55 the bank or group of keys 71 is used for the tens of feet.

Beneath the sliding plate 69 is a sliding plate 74. The sliding plate 74 has an enlarged portion 75 extending upwardly in 60 which are formed apertures for a key or

keys 76. Said key or keys 76 are mounted in the plate 77 and may be of the same general construction as the keys previously described. The key or keys 76 coöperate with one or more slots in a stationary plate 78 70 fixed upon the bed 79 of the frame of the machine. The enlarged upwardly extending portions 67, 70 and 75 serve as stops respectively for the various plates to the right thereof in Fig. 5, as they are brought together for a new distance setting when the keys of a previous setting are restored or retracted, and also bring the different banks of keys to the same level.

Referring more particularly to the slots 80 in the various plates with which the keys carried by the sliding plate thereabove coöperate, a series of slots 80 are formed in the plate 65 into which slots the keys carried by the plates 40 and 44 may be selectively projected. Each slot 80 coöperates with two of the keys in the plate 40, the position of the two keys along the slots effecting the difference in their setting or distance reading. The successive slots 80 90 will be of different lengths so as to give with the keys readings for the various inches over an integral foot as may be required. In the plate 69 are formed a series of slots 95 81 (Figs. 5 and 6) coöperating with the keys carried by the plate 80, and corresponding to the foot or feet settings. These slots are of varying lengths as may be required. Similar slots 82 are formed in the plate 74 to coöperate with the keys carried by the 100 plate 69, same being used in the present embodiment for the tens of feet. Slots 83 are formed in the stationary plate 78 into which slots the key or keys 76 may be set or projected to determine the reading of the device for either of two or more punching mechanisms, such as y and z located at different points longitudinally along the path of travel of the shape.

According to one feature of the invention 110 the ultimate or final readings, which in this case would be fractions of an inch, are made upon the cylinder 30, said settings or readings in the present embodiment being for sixteenths of an inch.

115 Means are therefore provided in the present embodiment for taking care of fractions of an inch and it is obvious that the same can be applied to other denominations, or sub-divisions or sub-multiples thereof. In 120 such embodied form, the cylinder 33 has an extension 90 fixed thereto or integral therewith, of arcuate form, extending upwardly along or across the opening in the casing 23 and contiguous to and about the cylinder 125 30. Said plate 90 carries keys which co-operate with grooves in the cylinder 30, as hereinafter more fully described. Above the plate 90 is mounted a similarly shaped plate 91, spaced away therefrom by one or 130

- more supports 92. Mounted in apertures in the plates 90 and 91 are series or groups of keys numbered respectively 95, 96, 97 and 98. These keys are provided with suitable retracting springs 99, and also with suitable locking plates 100 which operate in a manner similar to the plate 48. In the surface of the cylinder 30 are formed a plurality of grooves or slots corresponding to the series of keys carried by the plate 90. Said slots or grooves are helically arranged and of the same pitch as the internal thread 24 of the casing 23 and likewise of same pitch with the thread 32. Said grooves or slots are numbered respectively 101, 102, 103 and 104. The four keys of each enumerated series carried by the plate 90 operates with one of the grooves in the cylinder 30 just described.
- 20 On the left hand face of the cylinder 30 (referred to Figs. 2, 8 and 9) there is formed a series of crown teeth 105, which teeth are of the same pitch as the thread 24, the thread 32, and the grooves 101—104.
- 25 A corresponding series of crown teeth 106 is formed on the right hand face of the nut 27 (referred to Fig. 2) facing and contiguous to the teeth 105. A suitable spring 107 lies in a groove or grooves in the faces 30 of the nut 27 and cylinder 30 to hold them apart except when pressed together by the action of the mechanism.
- 35 Suitable returning or restoring devices are provided for restoring or repositioning the mechanism between successive settings. As embodied, for the purpose of drawing together the sliding plates, a lug 108 is formed on plate 72, and has fixed thereto a rod 109 slidably supported in an apertured lug 110, which lug is carried by a plate 40, the rod 109 extending through and beyond the lug 110. Upon the extended end of the rod 109 is fixed a cross-head 111, both ends of said cross-head being apertured to receive rods 112 and 113. Coiled about the rods 112 and 113 are springs 114 and 115, which springs operate to draw the various sliding plates together after a setting has been made. A suitable spring 116 is fixed to the plate 40 and to the cylinder sleeve 31 to restore the cylinder 30.
- 40 The manner of operation of the mechanism just described, in addition to the statements already made, is substantially as follows:
- 45 The shape α is impelled forward by the rollers 1 against the head 15. A distance setting is made of the desired distance of travel by setting the proper keys, as by way of example one of the keys or pins in the tens of feet series, also one in the feet series, together with one of the keys in the inch series and one in the sixteenths-of-an-inch series. The mechanism may be constructed so that the setting of the pin repre-

resenting the fraction of an inch will permit the mechanism to start into operation. The head 15 is thus permitted to travel, and as it travels the shaft 19 will be rotated through the rack 16 and pinion 18.

70 As the shaft 19 rotates, the nut 26 on the squared part 25 of the shaft 19, will rotate with the shaft, and also by reason of its thread 27 meshing with the internal thread 24 of the casing 23, said nut 26 will travel 75 toward the right (referred to Fig. 2) within the casing 23. The connected devices up to the collar 29 will also travel to the right with the nut 27. This includes the nut 33 and the plate 40 connected thereto. The 80 plate 40 will slide along upon its bearings 42 and 43.

85 One of the keys 45 carried by the plate 40 has been set for the requisite number of inches, and by its setting was projected into the corresponding slot 80 in the plate 65. When the key 45 reaches the end of its slot 80, the slide 65 will be started into movement and will then travel with the plate 40, and the nut 26, and intervening connected 90 parts.

95 Correspondingly, the plate 69 will start into movement when the set key or pin 68 reaches the end of the corresponding or co-operating slot 81 in the plate 69. In like manner, when the pin or key 71 which has been set reaches the end of the co-operating slot 82, the plate 74 will start into movement. The movement of these various parts being proportional to the movement of the 100 shape α , it will be seen that the head 15 has been permitted to move the distance for which the distance determining device was set, and the shape α has been propelled forward by the rollers 1 the same required distance. The key or keys 76 may be set in co-operation with the slots 83, to give a further movement relatively to the fixed plate 78 to compensate for the difference in position of one or the other punching mechanism.

105 Referring to the setting for the fraction of an inch, the cylinder 30 at this time is held from lineal travel along the shaft 19 except as it may also be rotated, and thus 115 move relatively to the nut 33, which nut 33 is connected by the neck 34 to plate 40, said plate and the other sliding plates having the settable key and slot connections, said plates having reached the limit of their 120 travel for the particular setting. The rotation of the cylinder 30, however, through the engagement of its thread on the sleeve 31 with the internally threaded nut 33, will permit of sufficient additional translational 125 travel to give the requisite fractional setting or positioning of the work.

130 When any one of the keys or pins of either of the series 95, 96, 97 or 98 has been projected into the corresponding groove or

slot 101, 102, 103 or 104, (see Figs. 2, 3, 6, 8 and 9) the nut 26 and cylinder 30 are thus free to travel until the set pin reaches or comes in contact with the end of the corresponding groove. In other words, after the plates 40, 65, etc., have come to rest, the further movement of the nut 26 and cylinder 30 will be rotational as well as translational, by reason of the engagement of the crown teeth 105 and 106, and will measure from the last integral inch setting. As the nut 26 rotates farther, its teeth 106 pass into line angularly and then into mesh or contact with the teeth 105 on cylinder 30, through the yielding of the spring 107. As cylinder 30 turns, its sleeve 32 screws into nut 33 and thus allows for the necessary advance of the nut 26 which has its thread 27 meshing with the thread 24 of the casing 23. There is a corresponding rotation of the shaft 19 and consequently a corresponding travel of the head 15 and shape α for the set fraction of an inch.

The various set keys may be released or restored in a suitable manner, as by the setting of a "zero" key, or the plate 48 for each group or bank of keys may be manually slid or actuated by its up-turned end 116. Successive settings may be made for the desired distances as the shape progresses along, the restoring spring restoring the slides between or after the successive settings, as will be clearly understood without further description.

35 When the punching of a particular shape or beam is completed, the head 15 and rack 16, and the various parts of the distance determining device are restored to exact starting position. In the embodied form of such restoring means, a motor 120 is connected by a gear train 121 to the shaft 19. Said motor 120 may be operated automatically from a distance record device, such as a perforated sheet or strip, by a suitable circuit controlling a magnetic switch or other starting device, and it will be understood that various additional controls and connections may be supplied as found necessary, and if desired controls or connections of the general form and type shown in application Serial Number 814,380 of Theodore P. Payne, filed Jany. 26, 1914, may be employed.

The operation of the other devices shown or referred to will be understood without further explanation or description except as hereinbefore given.

From all the foregoing it will be understood that a machine is provided embodying and realizing the stated objects and advantages of invention, together with other objects and advantages. It will be also understood that changes may be made from the illustrated and described form of mechanism within the scope of the accompanying

claims without departing from the principles of the invention and without sacrificing its chief objects and advantages.

What I claim as my invention and desire to secure by Letters Patent is:—

1. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and devices for distributing the total movement of all said members between the various members, to control the travel and stopping of said shape relatively to said punching means.

2. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and devices for distributing the total movement of all said members between the various members, to control the travel and stopping of said shape relatively to said punching means, and means for restoring said relatively movable members.

3. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, selectively settable devices for distributing the total movement of all said members between the various members, to control the travel and stopping of said shape relatively to said punching means, and means for restoring said relatively movable members preparatory to a new setting.

4. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and devices mounted upon said relatively movable members for distributing the total movement

- of all said members between the various members, to control the travel and stopping of said shape relatively to said punching means.
5. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and selectively settable devices mounted upon said relatively movable members for distributing the total movement of all said members between the various members, to control the travel and stopping of said shape relatively to said punching means and means for restoring said relatively movable members preparatory to a new setting.
6. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and devices representing distance values for distributing the total movement of all said members between the various members, to control the travel and stopping of said shape relatively to said punching means.
7. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, selectively settable devices representing distance values for distributing the total movement of all said members between the various members, to control the travel and stopping of said shape relatively to said punching means, and means for restoring said relatively movable members preparatory to a new setting.
8. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and devices for distributing the total movement
- of all said members between the various members, to control the travel and stopping of said shape relatively to said punching means and spring means for restoring said relatively movable members.
9. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, selectively settable devices for distributing the total movement of all said members between the various members, to control the travel and stopping of said shape relatively to said punching means, and automatic means for restoring said relatively movable members preparatory to a new setting.
10. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, selectively settable devices for distributing the total movement of all said members between the various members, to control the travel and stopping of said shape relatively to said punching means, and spring means for restoring said relatively movable members preparatory to a new setting.
11. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and selectively settable devices mounted upon said relatively movable members for distributing the total movement of all said members between the various members, to control the travel and stopping of said shape relatively to said punching means and spring means for restoring said relatively movable members preparatory to a new setting.
12. A machine for punching structural shapes including in combination punching means, and means for successively progressing and stopping a shape in proper positions to be punched, said means including a plurality of members representing distance denominations and being movable relatively to each other, connections for causing said

- members to have a total movement proportionate to the travel of the shape, and selectively settable devices mounted upon said relatively movable members for distributing the total movement of all said members between the various members, to control the travel and stopping of said shape relatively to said punching means and automatic means for restoring said relatively movable members preparatory to a new setting.
13. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, selectively settable devices representing distance values for distributing the total movement of all said members between the various members, to control the travel and stepping of said shape relatively to said punching means, and automatic means for restoring said relatively movable members preparatory to a new setting.
14. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, and devices for distributing the total movement of all said members between the various members, to control the travel and stopping of said shape relatively to said punching means.
15. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, devices for distributing the total movement of all said members between the various members, to control the travel and stopping of said shape relatively to said punching means; and means for restoring said relatively movable members.
16. A machine for punching structural shapes including in combination punching means, and means for successively progressing and stopping a shape in proper positions to be punched, said means including a plurality of members representing distance de-
- nominations and having translational movement relatively to each other, connections for causing said members to have a total movement proportionate to the travel of the shape, and selectively settable devices for distributing the total movement of all said members between the various members, to control the travel and stopping of said shape relatively to said punching means.
17. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, selectively settable devices for distributing the total movement of all said members between the various members, to control the travel and stopping of said shape relatively to said punching means, and means for restoring said relatively movable members preparatory to a new setting.
18. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, devices for distributing the total movement of all said members between the various members, to control the travel and stopping of said shape relatively to said punching means, and automatic means for restoring said relatively movable members.
19. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, selectively settable devices for distributing the total movement of all said members between the various members, to control the travel and stopping of said shape relatively to said punching means, and automatic means for restoring said relatively movable members preparatory to a new setting.
20. A machine for punching structural shapes including in combination punching means, and means for successively progressing and stopping a shape in proper positions to be punched, said means including a plurality of members representing distance de-

- a plurality of members representing distance denominations and having translational movement relatively to each other, connections for causing said members to have a total movement proportionate to the travel of the shape, selectively settable devices for distributing the total movement of all said members between the various members, to control the travel and stopping of said shape relatively to said punching means, and spring means for restoring said relatively movable members preparatory to a new setting.
21. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, and devices mounted upon said relatively movable members for distributing the total movement of all said members between the various members, to control the travel and stopping of said shape relatively to said punching means.
22. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, and selectively settable devices mounted upon said relatively movable members for distributing the total movement of all said members between the various members, to control the travel and stopping of said shape relatively to said punching means.
23. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, selectively settable devices mounted upon said relatively movable members for distributing the total movement of all said members between the various members, to control the travel and stopping of said shape relatively to said punching means.
24. A machine for punching structural shapes including in combination punching

means, and means for successively progressing and stopping a shape in proper positions to be punched, said means including a plurality of members presenting distance denominations and having translational movement relatively to each other, connections for causing said members to have a total movement proportionate to the travel of the shape, and selectively settable devices representing distance values for distributing the total movement of all said members between the various members, to control the travel and stopping of said shape relatively to said punching means.

25. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, selectively settable means representing distance values for distributing the total movement of all said members between the various members, to control the travel and stopping of said shape and means for restoring said relatively movable members preparatory to a new setting.

26. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, selectively settable means representing distance values for distributing the total movement of all said members between the various members, to control the travel and stopping of said shape automatically operating spring means for restoring said relatively movable members preparatory to a new setting.

27. A machine for punching structural shapes including in combination punching means, and means for successively progressing and stopping a shape in proper positions to be punched, said means including a plurality of members representing distance denominations and being movable relatively to each other, connections for causing said members to have a total movement proportionate to the travel of the shape, and devices for causing said members to move together or relatively to each other, to distribute the total movement between the various members to control the travel and stopping of said shape relative to said punching means.

denominations and having translational movement relatively to each other, connections for causing said members to have a total movement proportionate to the travel of the shape, and selectively settable devices for causing said members to move translationally together or relatively to each other to distribute the total movement between the various members to control the travel and 10 stopping of said shape relatively to said punching means.

36. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, selectively settable devices for causing said members to move translationally together or relatively to each other to 20 distribute the total movement between the various members to control the travel and stopping of said shape relatively to said punching means, and means for restoring said relatively movable members preparatory to a new setting.

37. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, and devices representing distance values for causing said members to move translationally together or relatively to each other to distribute the total movement between the various members to control the travel and stopping of said shape relatively to said punching means.

38. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, and devices carried upon said relatively movable members for causing said members to move translationally together or relatively to each other to distribute the total movement between the various members to control the travel and stopping of said shape relatively to said punching means.

39. A machine for punching structural shapes including in combination punching means, and means for successively progressing and stopping a shape in proper positions to be punched, said means including a plurality of members representing distance denominations and having translational movement relatively to each other, connections for causing said members to have a total movement proportionate to the travel of the shape, and selectively settable devices carried upon said relatively movable members for causing said members to move translationally together or relatively to each other to distribute the total movement between the various members to control the travel and stopping of said shape relatively to said punching means.

40. A machine for punching structural shapes including in combination punching means, and means for successively progressing and stopping a shape in proper positions to be punched, said means including a plurality of members representing distance denominations and being movable relatively to each other, connections for causing said members to have a total movement proportional to the travel of the shape, and devices carried by said relatively movable members for engaging other of said relatively movable members to cause them to travel together to control the travel and stopping of the shape relatively to said punching means.

41. A machine for punching structural shapes including in combination punching means, and means for successively progressing and stopping a shape in proper positions to be punched, said means including a plurality of members representing distance denominations and being movable relatively to each other, connections for causing said members to have a total movement proportional to the travel of the shape, and selectively settable devices carried by said relatively movable members for engaging other of said relatively movable members to cause them to travel together to control the travel and stopping of the shape relatively to said punching means.

42. A machine for punching structural shapes including in combination punching means, and means for successively progressing and stopping a shape in proper positions to be punched, said means including a plurality of members representing distance denominations and being movable relatively to each other, connections for causing said members to have a total movement proportional to the travel of the shape, and devices representing distance values carried by said relatively movable members to cause them to travel together to control the travel and stopping of the shape relatively to said punching means.

43. A machine for punching structural

shapes including in combination punching means, and means for successively progressing and stopping a shape in proper positions to be punched, said means including 5 a plurality of members representing distance denominations and having translational movement with respect to each other, connections for causing said members to have a total movement proportional to the 10 travel of the shape, and devices carried by said relatively movable members for engaging other of said relatively movable members to cause them to travel together to control the travel and stopping of the shape 15 relatively to said punching means.

44. A machine for punching structural shapes including in combination punching means, and means for successively progressing and stopping a shape in proper positions 20 to be punched, said means including a plurality of members representing distance denominations and having translational movement with respect to each other, connections for causing said members to have a total 25 movement proportional to the travel of the shape, and selectively settable devices carried by said relatively movable members for engaging other of said relatively movable members to cause them to travel together to 30 control the travel and stopping of the shape relatively to said punching means.

45. A machine for punching structural shapes including in combination punching means, and means for successively progressing and stopping a shape in proper positions 35 to be punched, said means including a plurality of members representing distance denominations and having translational movement with respect to each other, connections 40 for causing said members to have a total movement proportional to the travel of the shape, and devices representing distance values carried by said relatively movable members for engaging other of said relatively 45 movable members to cause them to travel together to control the travel and stopping of the shape relatively to said punching means.

46. A machine for punching structural shapes including in combination punching means, and means for successively progressing and stopping a shape in proper positions 50 to be punched, said means including a plurality of members representing distance denominations and having translational movement with respect to each other, connections for causing said members to have a total movement proportional to the travel of the shape, and selective settable devices representing distance values carried by said relatively 55 movable members for engaging other of said relatively movable members to cause them to travel together to control the travel and stopping of the shape, relatively to said 60 punching means.

47. A machine for punching structural shapes including in combination punching means, and means for successively progressing and stopping a shape in proper positions to be punched, said means including a plurality of members representing distance denominations and having translational movement with respect to each other, connections for causing said members to have a total movement proportional to the travel of the 70 shape, selectively settable devices carried by said relatively movable members for engaging other of said relatively movable members to cause them to travel together to control the travel and stopping of the shape relatively to said punching means, and automatic means for restoring said movable members preparatory to a new setting.

48. A machine for punching structural shapes including in combination punching 85 means, and means for successively progressing and stopping a shape in proper positions to be punched, said means including a plurality of members representing distance denominations and being movable relatively to 90 each other, connections for causing said members to have a total movement proportional to the travel of the shape, a series of keys carried upon one of said members, and slots being formed in an adjacent movable 95 member into which said keys are projectable to cause said members to travel together to control the travel and stopping of said shape relatively to said punching means.

49. A machine for punching structural 100 shapes including in combination punching means, and means for successively progressing and stepping a shape in proper positions to be punched, said means including a plurality of members representing distance denominations and being movable relatively to 105 each other, connections for causing said members to have a total movement proportional to the travel of the shape, a series of keys representing distance values carried 110 upon one of said members, and slots being formed in an adjacent movable member into which said keys are projectable to cause said members to travel together to control the travel and stopping of said shape relatively 115 to said punching means.

50. A machine for punching structural shapes including in combination punching means, and means for successively progressing and stopping a shape in proper positions to be punched, said means including a plurality of members representing distance denominations and being movable relatively 120 to each other, connections for causing said members to have a total movement proportional to the travel of the shape, a series of keys, said series representing a distance denomination and the various keys of the series representing distance values, said keys being carried upon one of said members, 125 130

and slots being formed in an adjacent movable member into which said keys are projectable to cause said members to travel together to control the travel and stopping of 5 said shape relatively to said punching means.

51. A machine for punching structural shapes including in combination punching means, and means for successively progressing 10 and stopping a shape in proper positions to be punched, said means including a plurality of members representing distance denominations and having translational movement relatively to each other, connections 15 for causing said members to have a total movement proportional to the travel of the sheet, a series of keys carried upon one of said members and slots formed in an adjacent movable member into which said 20 keys are projectable to cause said members to travel together translationally to control the travel and stopping of said shape relatively to said punching means.

52. A machine for punching structural 25 shapes including in combination punching means, and means for successively progressing and stopping a shape in proper positions to be punched, said means including a plurality of members representing distance 30 denominations and having translational movement relatively to each other, connections for causing said members to have a total movement proportional to the travel of the sheet, a series of keys carried upon one 35 of said members and slots formed in an adjacent movable member into which said keys are projectable to cause said members to travel together translationally to control the travel and stopping of said shape relatively 40 to said punching means, and automatic means for restoring said relatively movable members preparatory to a new setting of said keys.

53. A machine for punching structural 45 shapes including in combination punching means, and means for successively progressing and stopping a shape in proper position to be punched, a series of relatively movable plates, connections for causing said 50 plates to have a total movement proportional to the travel of the shape, and devices for distributing the total movement of said plates between the various plates, to control the travel and stopping of said shape relatively to said punching means.

54. A machine for punching structural 60 shapes including in combination punching means, and means for successively progressing and stopping a shape in proper positions to be punched, a series of relatively 65 movable plates, connections for causing said plates to have a total movement proportional to the travel of the shape, and devices representing distance values for distributing the total movement of said plates be-

tween the various plates to control the travel and stopping of said shape relatively to said punching means.

55. A machine for punching structural shapes including in combination punching 70 means, and means for successively progressing and stopping a shape in proper positions to be punched, a series of plates having translational movement with respect to each other, connections for causing said plates to have a total movement proportional to the 75 travel of the shape and devices for distributing the total translational movement of said plates between the various plates, to control the travel and stopping of the shape relatively to said punching means.

56. A machine for punching structural shapes including in combination punching 80 means, and means for successively progressing and stopping a shape in proper positions to be punched, a series of plates having 85 translational movement with respect to each other, connections for causing said plates to have a total movement proportional to the 90 travel of the shape and devices representing distance values for distributing the total translational movement of said plates between the various plates, to control the travel and stopping of the shape relatively to said punching 95 means.

57. A machine for punching structural shapes including in combination punching 100 means, and means for successively progressing and stopping a shape in proper positions to be punched, a series of plates having 105 translational movement with respect to each other, connections for causing said plates to have a total movement proportional to the travel of the shape, selectively settable devices for distributing the total translational movement of said plates between the various plates, to control the travel and stopping of the shape relatively to said punching means, and means for restoring said plates preparatory to a new setting of said settable devices.

58. A machine for punching structural 110 shapes, including in combination punching means, and means for successively progressing and stopping a shape in proper positions to be punched, a series of plates arranged 115 face to face and being relatively movable, connections for causing said plates to have a total movement proportional to the travel of the shape, and devices for distributing the total movement of said plates between the various plates, to control the travel and stopping of said shape relatively to said punching means.

59. A machine for punching structural 120 shapes including in combination punching means, and means for successively progressing and stopping a shape in proper positions to be punched, a series of plates arranged 125

- face to face and being relatively movable, connections for causing said plates to have a total movement proportional to the travel of the shape, and selectively settable devices representing distance values for distributing the total movement of said plates between the various plates, to control the travel and stopping of said shape relatively to said punching means.
60. A machine for punching structural shapes including in combination punching means, and means for successively progressing and stopping a shape in proper positions to be punched, a series of plates arranged face to face and having translational movement with respect to each other, connections for causing said plates to have a total movement proportional to the travel of the shape, and devices for distributing the total movement of said plates between the various plates to control the travel and stopping of said shape relatively to said punching means.
61. A machine for punching structural shapes including in combination punching means, and means for successively progressing and stopping a shape in proper positions to be punched, a series of plates arranged face to face and having translational movement with respect to each other, connections for causing said plates to have a total movement proportional to the travel of the shape, and selectively settable devices for distributing the total movement of said plates between the various plates to control the travel and stopping of said shape relatively to said punching means.
62. A machine for punching structural shapes including in combination punching means, and means for successively progressing and stopping a shape in proper positions to be punched, a series of plates arranged face to face and having translational movement with respect to each other, connections for causing said plates to have a total movement proportional to the travel of the shape, and selectively settable devices representing distance values for distributing the total movement of said plates between the various plates to control the travel and stopping of said shape relatively to said punching means.
63. A machine for punching structural shapes including in combination punching means, and means for successively progressing and stopping a shape in proper positions to be punched, a series of plates arranged face to face and being relatively movable, connections for causing said plates to have a total movement proportional to the travel of the shape, a series of keys carried upon one of said plates and adapted to engage another of said plates to control the travel and stopping of said shape relatively to said punching means.
64. A machine for punching structural shapes including in combination punching means, and means for successively progressing and stopping a shape in proper positions to be punched, a series of plates arranged face to face and being relatively movable, connections for causing said plates to have a total movement proportional to the travel of the shape, a series of keys, said series of keys representing a distance denomination and the individual keys representing distance values in said denomination, said keys being carried upon one of said plates and adapted to engage another of said plates to control the travel and stopping of said shape relatively to said punching means.
65. A machine for punching structural shapes including in combination punching means, and means for successively progressing and stopping a shape in proper positions to be punched, a series of plates representing respective distance denominations, and being arranged face to face and being relatively movable, connections for causing said plates to have a total movement proportional to the travel of the shape, a series of keys carried upon one of said plates and adapted to engage another of said plates to control the travel and stopping of said shape relatively to said punching means.
66. A machine for punching structural shapes including in combination punching means, and means for successively progressing and stopping a shape in proper positions to be punched, a series of plates arranged face to face and being relatively movable, connections for causing said plates to have a total movement proportional to the travel of the shape, a series of keys carried upon one of said plates and adapted to engage another of said plates to control the travel and stopping of said shape relatively to said punching means, and means for restoring said plates preparatory to a new setting of said keys.
67. A machine for punching structural shapes including in combination punching means, and means for successively progressing and stopping a shape in proper positions to be punched, said means including a plurality of members representing distance denominations and being movable relatively to each other, connections comprising a shaft rotating proportionately to the travel of the shape for causing said members to have a total movement proportionate to the travel of the shape, and devices for distributing the total movement of all said members between the various members, to control the travel and stopping of said shape relatively to said punching means.
68. A machine for punching structural shapes including in combination punching means, and means for successively progressing and stopping a shape in proper posi-

tions to be punched, said means including a plurality of members representing distance denominations and being movable relatively to each other, connections comprising a shaft 5 rotating proportionately to the travel of the shape for causing said members to have a total movement proportionate to the travel of the shape, and devices for causing said members to move together or relatively to each other to distribute the total movement 10 between the various members to control the travel and stopping of said shape relatively to said punching means.

69. A machine for punching structural shapes including in combination punching means, and means for successively progressing and stopping a shape in proper positions to be punched, said means including a plurality of members representing distance 15 denominations and being movable relatively to each other, connections comprising a shaft rotating proportionately to the travel of the shape for causing said members to have a total movement proportional to the travel 20 of the shape, and devices carried by said relatively movable members for engaging other of said relatively movable members to cause them to travel together to control the travel and stopping of the shape relatively 25 to said punching means.

70. A machine for punching structural shapes including in combination punching means, and means for successively progressing and stopping a shape in proper positions 30 to be punched, said means including a plurality of members representing distance denominations and being movable relatively to each other, connections comprising a shaft 35 rotating proportionately to the travel of the shape for causing said members to have a total movement proportional to the travel of the shape, a series of keys carried upon one of said members and slots being formed in an adjacent movable member into which 40 said keys are projectable to cause said members to travel together to control the travel and stopping of said shape relatively to said 45 punching means.

71. A machine for punching structural shapes including in combination punching means, and means for successively progressing and stopping a shape in proper positions 50 to be punched, a series of relatively movable plates, connections comprising a shaft rotating proportionately to the travel of the shape, for causing said plates to have a total movement proportional to the travel of the shape, and devices for distributing the total movement of said plates between the various 55 plates, to control the travel and stopping of said shape relatively to said punching means.

72. A machine for punching structural shapes including in combination punching 60 means, and means for successively progressing 65

ing and stopping a shape in proper positions to be punched, a series of plates arranged face to face and being relatively movable, connections comprising a shaft rotating proportionately to the travel of the shape, for 70 causing said plates to have a total movement proportional to the travel of the shape, and devices for distributing the total movement of said plates between the various plates, to control the travel and stopping of said shape 75 relatively to said punching means.

73. A machine for punching structural shapes including in combination punching means, and means for successively progressing and stopping a shape in proper positions 80 to be punched, a series of plates arranged face to face and having translational movement with respect to each other, connections comprising a shaft rotating proportionately to the travel of the shape for causing 85 said plates to have a total movement proportional to the travel of the shape, and devices for distributing the total movement of said plates between the various plates to control the travel and stopping of said shape 90 relatively to said punching means.

74. A machine for punching structural shapes including in combination means for traveling a shape along a substantially horizontal pathway, a member in engagement 95 with and extending along the shape and traveling therewith, a rotating shaft connected directly to said member to rotate proportionately to the travel of said member, a nut rotating with said shaft and having an external thread, a casing extending along said shaft and having an internal thread engaging the external thread in said nut, a plurality of slidable plates superimposed one upon another, some of said plates 100 having slots therein of various lengths, groups of keys representing distance denominations and values, the group of keys for a particular distance denomination being carried by one slidable plate, and another such group being carried by another of said plates, the various keys in a group being settable to represent numerical values 105 of said distance denominations and being thereby projected into a slot in an adjacent plate to determine the distance of travel of said plate and nut.

75. A machine for punching structural shapes including in combination means for traveling a shape along a substantially horizontal pathway, a head engaging the forward end of said shape, a rack fixed to said head and extending along said shape, a shaft and a pinion thereon engaging said rack, a nut slidable along but rotating with 120 said shaft and having an external thread, a casing extending along said shaft and having an internal thread engaging the external thread on said nut, a slidable plate connected to said nut to travel longitudi- 125 130

- 5 nally therewith, a group of keys carried by said plate and representing a distance denomination and values therein, a plurality of slidable plates, each of said plates having a plurality of slots therein of various lengths, said plates being in superimposition with said first mentioned plate, groups of keys carried by said plates, the keys on one plate being settable to engage the slots 10 on a next adjacent plate, and a stationary slotted plate coöperating with the last of said superimposed, key-equipped plates.
- 15 76. A machine for punching structural shapes including in combination means for traveling a shape along a substantially horizontal pathway, a head engaging the forward end of said shape, a rack fixed to said head and extending along said shape, a shaft and a pinion thereon engaging said 20 rack, a nut slidable along and rotating with said shaft and having an external thread, a casing extending along said shaft and having an internal thread engaging the external thread on said nut, a slidable plate connected to said nut to travel longitudinally therewith, a group of keys carried by said plate and representing a distance denomination and value therein, a plurality of slidable plates, each of said plates having a 25 plurality of slots therein of various lengths, said plates being in superimposition with said first mentioned plate, groups of keys carried by said plates, the keys of one plate being settable to engage the slots on a next adjacent plate, and a stationary slotted plate coöperating with the last of said superimposed, key-equipped plates and means operating automatically to restore said plates preparatory to a new setting of the keys.
- 30 77. A machine for punching structural shapes including in combination means for traveling a shape along a substantially horizontal pathway, a head engaging the forward end of said shape, a rack fixed to said head and extending along said shape, a shaft and a pinion thereon engaging said 35 rack, a nut slidable along but rotating with said shaft and having an external thread, a casing extending along said shaft and having an internal thread engaging the external thread on said nut, a sleeve fixed to said nut and embracing said shaft, a cylinder rotatably mounted on said sleeve, helical slots 40 in the exterior of said cylinder, said cylinder having an extension provided with an external screw thread, said cylinder and said nut having each crown teeth adapted to engage each other, means yieldingly holding said teeth out of engagement with each other, a member encircling said externally threaded portion of said cylinder and having an internal screw thread engaging said externally threaded portion of said 45 cylinder, and a slidable plate fixed with respect to said encircling member and traveling therewith, a group of keys mounted on said plate and corresponding to distance values, a plate adjacent to said slidable plate and having a plurality of key-receiving slots 50 therein of various lengths corresponding to the same distance values of said keys, means for restoring said plates with respect to each other after the keys of a setting are withdrawn.
- 55 78. A machine for punching structural shapes including in combination means for traveling a shape along a substantially horizontal pathway, a head engaging the forward end of said shape, a rack fixed to said head and extending along said shape, a shaft and a pinion thereon engaging said rack, a nut slidable along but rotating with said shaft and having an external thread, a casing extending along said shaft and having an internal thread engaging the external thread on said nut, a sleeve fixed to said nut and embracing said shaft, a cylinder rotatably mounted on said sleeve, helical slots 60 in the exterior of said cylinder, said cylinder having an extension provided with an external screw thread, said cylinder and said nut having each crown teeth adapted to engage each other, means yieldingly holding said teeth out of engagement with each other, a member encircling said externally threaded portion of said cylinder and having an internal screw thread engaging said externally threaded portion of said cylinder, and a slidable plate fixed with respect to said encircling member and traveling therewith, a group of keys mounted on said plate and corresponding to distance values, a plate adjacent to said slidable plate and having a plurality of key-receiving slots 65 therein of various lengths corresponding to the same distance values of said keys, means for restoring said plates with respect to each other after the keys of a setting are withdrawn.
- 70 79. A machine for punching structural shapes including in combination a rack traveling with the work, a shaft rotated by said rack, a moving member having translational movement proportional to the travel of the work, settable means representing distance values for arresting said moving member to stop said shaft and the work at a point in its travel for which said settable means are set.
- 75 80. A machine for punching structural shapes including in combination a member traveling with the shape, a rotary member connected thereto and rotating proportionately to the travel of the work, and means having translational travel for arresting said rotary member and the work at a desired point.
- 80 81. A machine for punching structural shapes including in combination a member traveling with the shape, a rotary member connected thereto and rotating proportionately to the travel of the work and means having translational travel and settable dis-

tance value devices for arresting said rotary member and the work at a desired point.

82. A machine for punching structural shapes including in combination tool 5 equipped means, means for traveling the work past said tool equipped means, a plurality of members having translational travel relatively to each other, and means for controlling such relative translational travel of 10 said members to stop and position the work relatively to said tool equipped means.

83. A machine for punching structural shapes including in combination punching means, and means for successively progressing and stopping a shape in selected posi- 15

tions to be punched, said means including distance determining devices comprising a plurality of members movable proportionately to the shape and having means for engaging each other so as to move together, 20 their total movement being proportional to the total movement of the shape.

In testimony whereof, I have signed my name to this specification, in the presence of two subscribing witnesses.

LOUIS A. HAWTHORNE.
